(57) **CLAIM**

The ornamental design for a lunch box lid, as shown and described.

DESCRIPTION

FIG. 1 is a first perspective view of a lunch box lid showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a sectional view thereof, taken along the dot-dash lines 9-9 in FIG. 7.

The broken lines shown in the drawings are for the purpose of illustrating portions of the lunch box lid and forms no part of the claimed design. The dot-dash lines shown in the FIG. 7 drawing are for the purpose of indicating the plane upon which the sectional view is taken and forms no part of the claimed design.

1 Claim, 9 Drawing Sheets
